FRANK Y. PEARNE, OF LOS ANGELES, CALIFORNIA.

PUNCHING AND RIVETING MACHINE.

1,305,972.

Specification of Letters Patent. Patented June 3, 1919.

Application filed May 11, 1916. Serial No. 96,822.

To all whom it may concern:

Be it known that I, FRANK Y. PEARNE, a citizen of the United States, and residing in Los Angeles, in the county of Los Angeles and State of California, have invented a new and useful Improvement in Punching and Riveting Machines, of which the following is a specification.

This invention relates to punching and riveting machines and more especially to machines of that character called "round seamers" for joining sections of pipe formed of sheet metal by "side seaming" and the principal object of the invention is to provide a tool carrier in which the tools may be adjusted without delaying the work thereon.

It is also an object of the invention to reduce the number of tools used and the time to effect their change, since the ease of adjustment allows of the double use of one of the tools carried thereby.

It is a further object of the invention to provide for this combined adjustment and change of tool, a single mechanism that will operate the same easily and quickly, locking the tools at the same time in the desired position and adjustment.

In the drawings accompanying this specification,

Figure 1, is a side elevation of a "round seamer" of well known form showing the improved tool carrier applied thereto, the combined tool being shown as laying the lap after the same has been riveted.

Fig. 2 is a front elevation of the improved tool carrier on a larger scale in the unengaged position in relation to the stake shown, a portion of the head and carrier being broken away to clearly show the guiding means for the tool holders.

Fig. 3 is a central vertical section through the head and tool carrier showing the mechanism for adjusting the tool holders the carrier being in the same position as shown in Fig. 2 but the holder having a punch inserted being in operative position.

In the use of punches, riveters and lap layers in machines of the class described it is a common method to shift the same in a plane transversely to the stake, thus requiring a shiftable member in the stake to successively act as an anvil and a die in the plane of the tools, complicating the movements by the operator and frequently resulting in accidents and loss of time.

In mechanisms in which the tools are shifted in planes of their own, there is lack of adjustment; necessary because of the wearing of the tools and variations in the thickness of stock.

This invention overcomes the above difficulties by providing an adjustable mechanism for the tools, thereby reducing the number required as already pointed out, as well as placing the tools in line with the axis of the stake so that this portion of the machine need not be weakened, thereby increasing the life of the stake as well as providing a convenient means of relieving undue strain.

Numerals are used throughout the drawing to designate the different parts of the mechanism, 5 designating the frame designed to rest upon and be secured to a foundation approximately level with the floor, and being provided with the arm 6 extending upwardly and outwardly over the stake 7.

The arm preferably terminates in a head 8, there being sufficient "throat" or clearance provided to accommodate one or more sections of pipe as desired, this arm and head forming bearings for the shaft 9, which is provided with the drive wheel 10 and dog clutch 11, operated by foot or otherwise to reciprocate the tool carrier 12 slidably mounted in the vertical slides of the head 8.

A sliding block 14 in the carrier embraces the eccentric 15 on the shaft 9, the shaft as is customary extending beyond the eccentric and being provided with a brake 16 and holes in the end 17 to receive a hand operating lever for turning the shaft slowly for adjustment and testing purposes.

A plate 18 secured to the front of the head confines the carrier within the slides, this plate being preferably cut away to accommodate a boss or extension of the carrier on which is fixed the circular plate 19, provided with the ring of detent holes 20 to lock the operating handle 21 of the tool shifting and adjusting mechanism.

This latter mechanism is preferably enclosed within a recess in the carrier, the only moving parts exposed being the lower end of the tool holder in operative position and the handle 21. The tool holders are shown as cylindrical members 22 and 23, provided with tool receiving sockets in their lower ends for the punch 24 and combined lap layer and riveter 25 respectively.

The upper portions of these holders 22 and 23 are threaded and are adapted to be reciprocated or lowered and raised by their engagement with the interiorly threaded 5 nuts 26 and 27, these nuts being supported in fixed axial relation within a recess above the bores provided for the tool holders, resting upon the hardened plate 28 provided with bores registering with those provided 10 for the holders and the thrust falling or striking upon the upper hardened plate 29, provided with alined bores to receive the trunnions 30 and 31 formed on the upper ends of the nuts 26 and 27. 15 The upper ends of these nuts are differently formed each however having the same area bearing against the plate 29 the nut 27 being so formed as to receive the gear wheel of bevel type 32 keyed thereon in any suitable manner, the nut 26 being cut away to provide clearance for the bevel gear 32, the lower ends of each however being formed with gear teeth cut thereon that mesh with each other and provide for turning these 25 nuts in unison, these gears being 33 and 34 respectively.

The bevel gear 32 is adapted to mesh with a gear 35 mounted with its trunnion 36 in the plate 15, a suitable boss 37 being 30 formed thereon to provide a bearing and being concentric with the ring of detent holes 20, the trunnion preferably extending beyond the bearing and having fixed thereto on the crank 38 of the handle 21 previously 35 mentioned.

A detent pin 40 pressed out by a spring 41 in a bore in the handle is of such length as to bear in the detent holes in the plate 19, those shown in the drawing providing 40 for an adjustment of one sixty-fourth of an inch in a one and three-eighths stroke shown, one revolution of the handle completely shifting the tools so that the handle is always in the same relative position during operation of the tools.

Various other methods may be evolved for turning the nuts which may be entirely threaded, or only for the distance where there is complete travel of the threads of 50 the tool holders, and other features may be altered without departing from the spirit of the invention.

The operation will be readily understood, the two sections of pipe to be joined being 55 approximated on the stake and the ends forced together the distance required for the lap, the lapping tool is brought into proper adjustment to force down or "lap" the "bell" formed on the end of the inner portion of 60 the lap or inner section.

For this purpose the shaft and eccentric with the carrier must be in a position judged by the experience and skill of the operator, the handle being turned contra-clockwise to 65 advance the lapping tool and the reverse to

place the punch in operative position, this punching tool being operated after the first lap is laid, after which the pipe is again shifted to receive the rivets, and the latter brought into the plane of the lapping tool, 70 the shaft being disengaged and the carrier and riveting tool adjusted to accommodate the increase of the thickness or length of the rivet.

With the riveting completed, it being understood that when the latter were inserted the heads were necessarily and preferably inside the pipe, the pipe is again shifted outward until the outside lap or outside "bell" comes under the lap laying tool, the latter being lowered or advanced from the last position, by turning the handle counter-clockwise a few degrees or "detents" to bring the stroke nearer the stake.

Should such an emergency arise after the clutch has been thrown, the tool in position may be relieved by quickly turning the handle 21 in the proper direction, or the advance increased without stopping the machine.

To guide the tool holders and keep the same from turning keys 42 and 43 are provided, that fit keyways cut in the holders, a plate 44 holding the same in position. An anvil 45 and die 46 are inserted in the stake 7 in proper positions.

What I claim is:

1. A punching tool carrier, comprising in combination with a press adapted to reciprocate said carrier, of a carrier, intermeshing gears mounted therein, and a plurality of tools mounted in said carrier and so connected by said intermeshing gears that said tools may be alternately thrown into or out of operative position.

2. A punching tool carrier having a plurality of bores therein parallel to and adjacent one another, tool holders adapted to slide therein, members engaging said holders to effect the movement and adjustment thereof, and means to move said engaging members in unison.

3. In a pipe making machine provided with a stake and means to reciprocate a tool carrier, the combination of a tool carrier adapted to be reciprocated by said reciprocating means, a pair of tool holders adapted to hold tools, and be movably mounted in said tool carrier, and geared interconnecting means to move one or the other of said holders intermediate the ends of their stroke, so as to perform operations on materials requiring a variation of the stroke of the tool carried thereby.

4. In a pipe seamer provided with a head, stake and means to reciprocate a tool carrier reciprocally mounted in said head, the combination of a tool carrier provided with a pair of bores parallel to each other and in line with the axis of the stake on said seamer, and entering a recess in said carrier,

tool holders slidably mounted in said bores and of such length as to be housed therein, and means mounted in said recess to connect said tool holders, whereby, when one is projected from said carrier, said other tool holder with its tool will be drawn out of operative position in relation to said stake.

5 5. A round seamer for riveting pipe, comprising a frame having an arm extending over a stake, a head on said arm, a stake, a tool carrier slidably mounted in said head, means to slide said carrier toward and from said stake, a pair of threaded tool holders slidably mounted in said carrier, threaded 10 members mounted in said carrier and adapted to engage said threaded tool holders, and means to move said threaded members, whereby said holders are alternately extended from said carrier, that tools carried there- 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510

6. A round seamer for riveted pipe comprising a frame, an arm, a head on said arm, a stake on said frame in line with said arm, a reciprocating tool carrier, means to reciprocate said carrier in said head, a pair of threaded tool holders mounted in said carrier, means to guide said holders, threaded nuts engaging said threaded tool holders and revolvably mounted in said carrier, and means to revolve said nuts in unison where-

by said tool holders are alternately projected from said carrier.

7. A seaming press comprising in combination with a head and stake carrying 35 frame, together with driving means, of a tool carrier reciprocatively mounted in said head, a punch slidably mounted in said carrier, a combined lap laying and riveting tool slidably mounted in said carrier and 40 in the same plane with said stake and punch, keys adapted to engage keyways in said punch and tool, and gears connecting said punch and tool, whereby one or the other will be in operative and adjustable relation 45 to each other and to work carried on said stake.

8. A seaming machine for seaming pipe, comprising a frame, a stake supported thereon, a head, a sliding carrier mounted in said 50 head, means to move said carrier, a pair of tool holders slidably mounted in said carrier and adapted to hold tools, means engaging said holders to slide the same in opposite directions, gears on said engaging 55 means, means to turn said gears to move said tool holders to adjust tools held therein or alternate the operative relation thereof, and means to lock said means to turn said gears, intermediate the end positions of said 60 tools.
